(57) **CLAIM**

An ornamental design for a body position sensor device, as shown.

DESCRIPTION

FIG. 1 is a front perspective view of the device;
FIG. 2 is a rear perspective view of the device;
FIG. 3 is a front view of the device;
FIG. 4 is a right side view of the device;
FIG. 5 is a left side view of the device;
FIG. 6 is a rear view of the device;
FIG. 7 is a top view of the device; and,
FIG. 8 is a bottom view of the device.
